UNITED STATES PATENT OFFICE.

ALVA L. REYNOLDS, OF LONGBEACH, CALIFORNIA.

HYDRAULIC-POWER SYSTEM.

1,074,292.

Specification of Letters Patent. Patented Sept. 30, 1913.

Application filed August 14, 1912. Serial No. 715,115.

To all whom it may concern:

Be it known that I, ALVA LEEMAN REYNOLDS, a citizen of the United States, residing at Longbeach, in the county of Los Angeles and State of California, have invented new and useful Improvements in Hydraulic-Power Systems, of which the following is a specification.

This invention is applicable in connection with features of my earlier invention entitled improvements in water power systems, No. 988,508, patented Apr. 4, 1911, and principally differs from said earlier invention in respect to the driving of the pumps which in the earlier invention were driven by vertically pivoted vanes more particularly designed for utilizing the force of ocean waves whereas in this present invention the vanes are horizontally pivoted so as to be more especially adapted for using the steadier force of river or channel currents having or not having tidal action.

An object of this invention is the provision of novel means whereby the pumps of a system may be individually driven by a flowing stream of water.

Another object is to effect the driving in such manner that fluctuations in the height of the stream caused by tidal action or otherwise will be compensated for.

Another object is to effect the driving in such manner that power may be derived from a stream flowing at different periods of time in reverse directions as would occur in tidal rivers.

Other objects and advantages may appear from the subjoined detail description.

The accompanying drawings illustrate the invention.

Figure 1 is a perspective view of apparatus embodying the invention. Fig. 2 is an enlarged fragmentary plan view of Fig. 1, the pier floor being omitted to expose to view the parts beneath. Fig. 3 is a cross section of a floating paddle-wheel on line $\alpha\alpha'$, Fig. 2.

A turbine-generator set 1 or other hydraulically-operated device is connected in multiple by a pressure main 2, sump 3 and supply main 4 to pumps 5 preferably double-acting; and the pressure main 2 may be provided intermediate of the turbine-generator set and pumps with an air-pressure tank 6 and a pressure gage 7, all of which have been substantially shown and specifically described and claimed in the herein-

before mentioned patent and are not herein claimed. In this instance the pump pistons 8 reciprocate through bearings 9 at their outer ends and are provided with wrist-blocks 10 which pivot vertically swinging pitmen 11 that are connected to crank shafts 12 journaled in bearings 13. Each crank-shaft 12 is provided at one end with a sprocket wheel 14 driven by a sprocket chain 15 which is driven in turn by a sprocket wheel 16 rotatably mounted on a hanger shaft 17 that extends between supports as the piles 18 and that is suitably fastened at its ends by sockets 19 and bolts 20 to the piles and that may be supported intermediate of its ends by hanger brackets 21 which are fastened by means, not shown, to the pier floor α . Each sprocket wheel 16 is driven by and may be integral with a bevel gear 22 meshing with a bevel gear 23 fixed on one end of a gear shaft 24 which is provided at its other end with a bevel gear 25 and which is journaled by bracket bearings 26 that are supported on one of a pair of spaced-apart radius arms 27 which are pivoted at their upper ends by journal-boxes 28 to the hanger shaft 17. By this construction it is seen that the bevel gear 23 can swing in an arc of which its generating axis is coincident with the axis of the bevel gear 22.

The hanger shaft 17 may be provided with thrust collars 29 on both sides of the radius arms to keep them from sliding along the shaft. The radius-arms 27 of each pair are provided at their lower ends with boxes 30 journaling a wheel-shaft 31 which is provided with a bevel gear 32 in mesh with and driving the bevel gear 25 and on which is mounted a buoyant paddle wheel 33 to drive the wheel shaft.

From the foregoing it is clear that any up-and-down movement of the paddle wheel 33 will not affect the driving connections 100 and it is also clear that the driving connections may be otherwise constructed to obtain this result.

The wheel-shaft 31 may be suitably provided with thrust collars 29' to prevent endwise movement of the paddle wheel 33. Each paddle wheel 33 in its preferred form of construction comprises a cylindrical shell 34 of metal or wood having longitudinal slots 35 through which vanes or paddles 36 of metal or wood project radially inward to seat at their inner ends in longitudinal

grooves 37 of a core-sleeve 38 which may be keyed or otherwise fastened to the wheel-shaft 31 and to which the paddles may be fastened by bolts 39 or the like. The inter-paddle spaces 40 are filled with suitable material to effect such buoyancy of the paddle wheel 33 as will keep the wheel shaft 31 above the level of the water 42 and I have shown such material as a buoyant solid 10 which may be composed of a composition 41 of ground cork and asphaltum. The inter-paddle spaces 40 may be filled with the ground cork, and hot asphaltum then poured in so as to seal the shell and effectually exclude water from the interior, thus making the paddle wheel buoyant and at the same time bracing the paddles against the thrust of the stream on their outer projecting ends.

In practical operation the radius arms 27 20 will extend in the direction of the current shown by small arrows and the paddle wheels 33 will rise or fall in accordance with the level of the water 42 and will drive the pumps 5 through the driving connections 25 to effect operation of the turbine-generator set 1 as set forth in my hereinbefore mentioned patent.

In tidal rivers when the current reverses as the tide ebbs and flows the direction of 30 rotation of the paddle wheels will be accordingly reversed, without any detrimental effect on the pump driving mechanism.

By constructing the paddle wheel in the manner set forth it is made practically non-sinkable and non-collapsible thus guarding 35 against submersion caused by leaks and also against breakage from floating bodies in the stream.

I claim:

40 1. In a hydraulic power system, a paddle-

wheel comprising a shell and a buoyant composition of cork and asphaltum in the shell.

2. A paddle-wheel comprising a shell with longitudinal slots, a core sleeve having longitudinal grooves, and paddles extending through the shell slots and into said grooves. 45

3. A paddle-wheel comprising a shell with longitudinal slots, paddles extending radially inward through the shell slots, and a 50 filling in the inter-paddle spaces of the shell.

4. A paddle-wheel comprising a shell with longitudinal slots, paddles extending radially inward through the shell slots, and a 55 buoyant filling in the inter-paddle spaces of the shell.

5. A paddle-wheel having a shell with longitudinal slots, paddles extending radially inward through the shell slots, and a 60 buoyant composition of cork and asphaltum in the shell.

6. A paddle-wheel having a shell with longitudinal slots, a core-sleeve having longitudinal grooves, paddles extending through the shell slots and into said grooves, 65 and a filling in the inter-paddle spaces of the shell.

7. A paddle-wheel having a shell with longitudinal slots, a shaft, a core sleeve fixed to the shaft and provided with longitudinal 70 grooves, paddles extending through the shell slots and into said grooves, and a filling in the inter-paddle spaces of the shell.

In testimony whereof, I have hereunto set my hand at Los Angeles, California, this 75 8th day of August, 1912.

ALVA L. REYNOLDS.

In presence of—

JAMES R. TOWNSEND,
GEORGE H. HILES.
